UNITED STATES PATENT OFFICE.

EDWARD T. FRAIM, OF LANCASTER, PENNSYLVANIA.

DESIGN FOR A PADLOCK-CASE.

SPECIFICATION forming part of Design No. 27,265, dated June 29, 1897.

Application filed June 18, 1896. Serial No. 596,078. Term of patent 7 years.

To all whom it may concern:

Be it known that I, EDWARD T. FRAIM, a citizen of the United States, residing at Lancaster, in the county of Lancaster and State 5 of Pennsylvania, have invented and produced a new and original Design for a Padlock-Case; and I do hereby declare the following to be a full, clear, and exact description of the same, reference being had to the accompanying 10 drawing, forming a part thereof.

The drawing presents a perspective view of a sprocket-chain padlock-case, showing my design.

The leading feature of my design consists 15 in the padlock-case A, having the general contour shown, being practically a parallelopiped in form with a cylindrical projection A' from the lower face and somewhat nearer to

one end thereof, which is rounded off, as shown at a, the entire surface of the case being perfectly smooth or polished and the end of the cylindrical projection provided with a key-hole. 20

Having now described my invention, what I do consider new, and desire to secure by Letters Patent, is— 25

The design for a padlock-case, substantially as hereinbefore described and shown in the drawing.

In testimony whereof I affix my signature 30 in presence of two witnesses.

EDWARD T. FRAIM.
